UNITED STATES PATENT OFFICE.

MICHAEL BROCHU, OF GRAND RAPIDS, MICHIGAN, ASSIGNOR OF ONE-THIRD TO JOHN D. RAAB AND ONE-THIRD TO ANTHONY DISK, OF GRAND RAPIDS, MICHIGAN.

METALLIC CASK.

1,169,084.

Specification of Letters Patent. Patented Jan. 18, 1916.

Application filed October 24, 1913. Serial No. 797,026.

To all whom it may concern:

Be it known that I, MICHAEL BROCHU, a citizen of the United States, residing at Grand Rapids, in the county of Kent and State of Michigan, have invented new and useful Improvements in Metallic Casks, of which the following is a specification.

My present invention relates to metallic casks; and its object is to provide a metallic cask having separable parts and similar generally to that described in my Patent No. 643,787 dated February 20, 1900, but improved thereover in certain respects, particularly the following: the provision of improved protecting and strengthening means for the cask; the provision of an air chamber surrounding the cask; the provision of means whereby the several parts of such improved structure may be readily disassembled for cleaning, etc., and easily reassembled; and the provision of such means in various combinations; and a further object of this, my present invention, is to provide a metallic cask improved in various respects hereinafter appearing. These objects are attained by, and the invention finds a preferable embodiment in, the structure herein-after described and illustrated by the accompanying drawings, in which:—

Figure 1 is a side view of such structure; Fig. 2 is a top plan view of the same; Fig. 3 is an axial section of such structure on line A—B of Fig. 2; Fig. 4 is a bottom plan view of the same; Fig. 5 is a side view of one of the cask halves, shown partly in axial section; Fig. 6 is a like view of the packing member; and Fig. 7 is a detail enlarged fragmentary view of the joint between the cask halves.

The cask comprises two parts, preferably halves, 1, 2, and formed preferably of stamped sheet metal, their open ends being provided with outwardly-extending flanges 3 concavo-convex in cross-section. A suitable round packing 4 is contained in the concave portion of the flanges and between the assembled halves 1, 2. Detachable clamping rings 5, 6 surround the cask halves respectively, abutting against the convex side of their flanges; these clamping rings are provided with suitable means, as the screw-threaded mutual engagement particularly shown in Fig. 3, whereby they may be drawn together to tightly connect the two cask halves. Heads 18, 7 are detachably

connected to the respective rings 5, 6 as by diametrically oppositely disposed screw-threaded rods 8, 9. The clamping rings, head, and screw-threaded rods, together with a suitable number of rods 10, extending between and detachably secured to the respective clamping rings and heads as by being let into suitable sockets 11 therein, form protecting means whereby the cask halves are kept from injury during transportation, etc. Metallic shells 12, 13 each in form the hollow frustum of a cone, surround the respective cask halves and are detachably connected to the heads and clamping rings, as by their edges being let into suitable annular grooves 14 in such heads and rings, and being securely held therein by the threaded rods 8, 9. It will be seen that these shells, together with the heads 18, 7, and the clamping rings, 70 form an air chamber surrounding the cask halves. In order to fill or empty the cask, a suitable plug 15 is provided, threaded into a boss 16 carried by one of the cask halves 1, and tightly engaging within an orifice 17 80 through the corresponding head 18.

It will be seen that all the parts of my improved cask, by means of the detachable connections shown, may be readily assembled and disassembled for the purposes of 85 cleaning, transporting, or storing the device.

Not confining myself to details of construction shown or described, I claim:

1. In a device of the character described, 90 a cask comprising two separable parts respectively provided with detachable clamping rings adapted to be drawn together to tightly connect the separable cask parts; heads outside the ends of said separable parts; cask-protecting members extending between the respective rings and heads; and means for detachably connecting the respective heads, rings and protecting members together.

2. In a device of the character described, 105 a cask comprising two separable parts each having a peripheral flange, detachable clamping rings adapted to engage the respective flanges and to be drawn together to tightly connect the separable cask parts; heads outside the ends of said separable parts; cask-protecting members extending between the respective rings and heads; and means for detachably connecting the re- 110

spective heads, rings and protecting members together.

3. In a device of the character described, a cask comprising two separable parts respectively provided with detachable clamping rings adapted to be drawn together to tightly connect the separable cask parts; heads outside the ends of said separable parts; cask-protecting members extending between the rings and heads; shells inside the cask-protecting members and extending between the respective heads and clamping rings, whereby an air chamber outside the cask is formed in the assembled position of the device; and means for detachably connecting the respective heads, rings, shells and protecting members together.

4. In a device of the character described, a cask comprising two separable parts respectively provided with detachable clamping rings adapted to be drawn together to tightly connect the separable cask parts; heads outside the ends of the said separable parts, the rings and heads having annular grooves; and shells detachably connected to the respective heads and clamping rings and engaging in said grooves, whereby an air

chamber outside the cask is formed in the assembled position of the device.

5. In a device of the character described, a cask comprising two separable parts respectively provided with detachable clamping rings adapted to be drawn together to tightly connect the separable cask parts; heads outside the ends of the said separable parts, the rings and heads having annular grooves and sockets; cask-protecting members extending between the rings and heads and let into said socket; shells inside the cask-protecting members, extending between the heads and rings and let into said grooves, whereby an air chamber outside the cask is formed in the assembled position of the device; and screw-threaded bolts extending between the respective rings and heads to detachably connect them and the cask-protecting members and shells together.

In testimony whereof I have hereunto set my hand in presence of two subscribing witnesses.

MICHAEL BROCHU.
